Joseph Blaeker
ATTORNEY

UNITED STATES PATENT OFFICE

HARRY ETKINS, OF NEW YORK, N. Y.

COMBINATION HEAD ROD AND PULLEY FIXTURE FOR AWNINGS

Application filed April 16, 1928. Serial No. 270,450.

This invention relates particularly to the hardware fixtures employed for mounting window awnings and for attaching the owning head rod to the window frame.

The main object of this invention is to provide an awning head rod fixture which presents an inseparable combination of the many separate pieces presently employed, that is, a hook, a head rod holder and pulleys.

Another object of this invention is to provide an inseparable combination head rod and pulleys fixture, the pulley blocks being cast directly upon and in swivelling junction with arms extending downwardly from the head rod holder.

Another object of this invention is to provide an inseparable combination head rod and pulleys fixture having a locking mechanism which can secure an awning head rod in position without in any way cutting or damaging the awning fabric.

Another object of this invention is to provide an inseparable combination head rod and pulleys fixture having a locking mechanism to secure an awning head rod in position and which can be used for wooden head rods as well as for iron head rods, the locking mechanism serving merely to hold the head rod in position and does not exert any clamping or cutting action on the rod or on the awning fabric.

With these and other objects in view the invention will be hereinafter more particularly described, and the combination and arrangement of parts will be shown in the accompanying drawings and pointed out in the claim which forms part of this specification. It being understood that various changes in the form, proportion, size and minor details of construction within the scope of the claim, may be resorted to without departing from the spirit or sacrificing any of the advantages of the invention.

In the simplest forms of awning installations it is common practice to secure an awning to a building by means of screw eyes screwed into the window frame and passing through grommets inserted at equally spaced distances along the top edge of the awning.

This method requires five screw eyes and as many holes in the window frame and is objected to because it results in the destruction of the framework. In the modern installations, the awning fabric at the top edge of the awning is wrapped around a metal or wooden head rod and is secured thereto. Only two head rod holders are necessary and this avoids the necessity of making too many holes, and it is this method of installation that the present invention aims to improve.

To install a window awning it is presently necessary to first, fasten a screw eye into the upper window sill; second, to hang a head rod holder on the screw eye; and third, to hang one or two pulley blocks on the head rod holder. Inasmuch as window awnings must be mounted and demounted each year, these loosely assembled awning mounting devices cause constant annoyance by being misplaced and hard to handle and do not fully meet the demand of the building industry for awning mounting hardware by means of which an awning may be quickly and easily mounted and demounted without any danger to the mechanic or damage to the awning fabric.

This invention provides an inseparable combination head rod and pulleys fixture for awnings which takes the place of the three or four separate and loosely assembled pieces.

Reference will now be had to the drawings, wherein like numerals of reference designate corresponding parts throughout the several views, in which:

Figure 1 is a perspective view of a head rod holder made in accordance with the subject matter of this invention and shows an awning head rod locked therein in operating position. At the bottom of the head rod holder are two downwardly extending arms having enlargements at their lower ends upon which pulley blocks may be cast.

Figure 2 is a front view of an assembled head rod holder having inseparably joined thereto one single pulley block and one double pulley block which have been cast directly upon the enlargements on the ends of the two downwardly extending arms.

Figure 3 is a side view of a combination

head rod and pulleys fixture showing an awning head rod and part of the awning fabric in place.

Figure 4 is a front view of a head rod holder assembly partly in section, the section being taken as on line $x-x$ in Figure 3, and showing only one centrally placed downwardly extending arm from the head rod holder.

10 Figure 5 is a sectional view of this head rod holder assembly, the section being taken as on line $y-y$ in Figure 4, with the locking member in an open position.

As shown in Figure 1, there has been provided a bracket 1, having thereon two right angularly disposed pivot arms 2, 2, and a right angularly disposed seat 3. The pivot arms are provided with holes for a pivot 4, which extends on each side of the pivot arms a sufficient distance to enable a locking member 5, to be mounted thereon. A fragmentary section of an awning head rod 6, is shown resting on the supporting seat 3, and locked in position by the locking member 5, which encircles part of the circumference of the head rod. Two circular arms 7 and 8 integral with the bracket extend downwardly from the bracket, and these arms have enlargements at their lower ends. The enlargements 9 and 10 are shown as semi-spherical, but may be semi-spherical, ball-shaped or disk-like, the object of the enlargements being to cast pulley blocks directly upon and in swivelling junction with them.

35 As shown in Figure 2, one single pulley block 11, and one double pulley block 12, have been cast directly upon the enlargements 9 and 10, at the ends of the arms 7 and 8, and are inseparably joined thereto. The pulley blocks can swivel around so as to face any direction from which the pulley rope may come, but under no circumstances can the pulley blocks be removed from the combination fixture without first breaking the metal of which the pulley block is cast.

40 As shown in Figure 3, the awning fabric 16 is wrapped around the head rod 6, and is secured thereto.

45 As shown in Figure 4, the lower end of the head rod holder bracket 1 is provided with a centrally placed downwardly extending arm 14, having an enlarged ball-shaped lower end 15, around which a pulley block may be cast in swivelling junction therewith. 50 There has also been provided two countersunk holes 17, 17, in the bracket 1, and these holes are used for fastening the bracket to the upper sill 18 of a window frame 19, the method of fastening being best shown in Figure 3. 55 Another hole 20 is provided at the center line of the bracket, and this hole serves as an auxiliary in cases where the fixture must be mounted upon a hook. The pivot 4 may be a copper rivet or a piece of copper wire, copper being used so that it will not corrode.

As shown in Figure 5, the locking member 5 is in an open position and the lock aperture 13 is free to receive a head rod.

It is to be noted that Figure 1 illustrates a head rod holder assembly, while Figure 2 illustrates a combination head rod holder and pulleys fixture. Two of these combination fixtures are mounted in a suitable position on the upper window sill about six inches from each end of the window frame. The locking member 5 is rotated to the open position shown in Figure 5, and the upper end of the awning containing the head rod 6 is then moved upwardly so that the head rod enters the lock aperture 13, and the locking member is then rotated away from the window to the locked position shown in Figure 3. When this operation has been repeated at both fixtures, the upper end of the awning is mounted in place and will remain there in one fixed position unless demounted by a mechanic.

50 To demount the awning the head rod 6 is pushed to the rear of the lock aperture 13, the locking member 5 is grasped and rotated to the open position shown in Figure 5 leaving a clear opening for the awning to move away from the window. It is to be noted that the locking member does not exert any clamping action on the head rod, but merely encircles part of its circumference and holds the head rod in position on the supporting seat.

55 The usual practice in the construction of pulley blocks for awnings is to cast the pulley block upon the arm of an eye member having a ball-shaped head around which the pulley block swivels, the eye serving to hang the pulley block loosely upon any kind of a hook. The present invention avoids the use of the swivelling eye member, the pulley blocks being cast directly upon the enlargements at the ends of arms extending downwardly from the head rod holder.

60 It is to be noted that the pivot 4 may be driven a tight fit into the holes of the pivot arms 2, 2, and that the locking member 5 is free to rotate about the pivot, and that the pivot may be riveted or hammered over slightly at the ends.

65 It is thus seen that there has been provided a combination head rod and pulleys fixture for awnings in which the component parts are inseparably united as a unit, and which permits an awning to be quickly and easily mounted and demounted, a combination head rod and pulleys fixture having a locking mechanism which will not damage the head rod or the awning fabric, and which presents a self-contained and finished appearance and the cost of which is within the limits of commercial requirements.

70 Having thus described my invention, I claim as new and desire to secure by Letters Patent:

75 In a combination head rod and pulleys fix-

ture for awnings, comprising a bracket casting for supporting a head rod, one or more downwardly extending arms having an enlargement at their lower ends, said arms being cast integral with the bracket, and one or 5 more pulley blocks cast directly upon the enlarged ends of the arm or arms and form an integral awning head rod and pulleys combination fixture in which the pulley blocks are inseparable from and in swivelling junction 10 with the head rod holder bracket substantially as described.

HARRY ETKINS.
